UNITED STATES PATENT OFFICE.

WASABUROW TAKESUYE, OF OGDEN, UTAH.

ROTARY FAN.

1,128,633.

Specification of Letters Patent. Patented Feb. 16, 1915.

Application filed December 6, 1913. Serial No. 805,020.

To all whom it may concern:

Be it known that I, WASABUROW TAKESUYE, a subject of the Emperor of Japan, residing at Ogden, in the county of Weber 5 and State of Utah, have invented new and useful Improvements in Rotary Fans, of which the following is a specification.

The invention has for one of its principal objects to enable the incorporation of a 10 manually operated rotary fan in the handle of a sunshade, whereby in sultry weather, not only may the handle be manipulated to shield the user from the sun, but by a simple movement of the fingers which will 15 not interfere with the grasp on the handle, a rotary fan on the side of the handle may be used to produce a cooling breeze.

A further important aim is to simplify the construction of the frame for the mechanism 20 and the method of mounting it whereby it is adapted peculiarly for the present use.

A further important object is to present such an arrangement of the parts that a 25 symmetrical casing may inclose them in a form and size which will be without objections as a part of an umbrella or the like.

Additional objects and advantages will appear, some of which will be apparent from 30 the following description and from the drawings, in which,

Figure 1 is a side view of a sunshade having a handle constructed in accordance with my invention; Fig. 2 is a detail longitudinal 35 sectional view of the mechanism. Fig. 3 is a side view of the mechanism and frame, the casing in section, Fig. 4 is a cross section of the handle. Fig. 5 is a detail of the handle showing the method of use. Fig. 6, is a 40 detail of a modified hand rest, showing a hand engaged therewith, Fig. 7, is a detail of the ferrule structure at the upper end of the frame, Fig. 8, is an outer end view thereof, Fig. 9, is a fragmentary view of a handle of modified construction.

There is illustrated a sunshade or umbrella 10, of any usual construction as regards the canopy and supports, the handle 11 of which, however is preferably attached 45 to the stem by means of a screw threaded shank 12. The handle may approximate the proportions of the usual umbrella or parasol handle, and comprises a symmetrical grip 13 in which there is secured the two sides of a frame 14 which comprises two pieces of thin strap metal suitably spaced

and apertured for the mounting of a train of gears to be described in detail, the upper ends of the pieces being inset rounded and threaded for engagement in the stem of the 60 umbrella. A shaft 16 is mounted revolvably closely adjacent the upper end of the frame 14, being carried in suitable apertures in the side pieces thereof, and a small gear 17 is secured thereon. The shaft has a 65 squared end projecting through the frame, upon which the correspondingly apertured hub 18 of a small screw-blade fan may be pressed and frictionally held. A double gear 19 is mounted revolvably below the 70 shaft 16, the large member of which is meshed with the gear 17, and the small member of which is in mesh with a large gear 20 revolvable upon a shaft 21, which latter is also mounted revolvably in the frame 14. 75 Fixed upon this shaft and serving to check the gear 20 against sliding movement in that direction, there is a ratchet wheel 22, engaged by a pawl 23 on the gear 20 the pawl being pressed by a spring 24 for proper operation. On the opposite side of the gear 20 a small gear 25 is fixed upon the shaft 21. The small gears above mentioned may be of the usual clock type. The gear 25 is engaged by a gear segment 26 mounted between the side pieces of the frame 14 closely adjacent the grip 13 against which it strikes 80 at one limit of its movement. The segment is engaged by a spring 27 having a helix engaged around the shaft 28 carrying the 85 segment, one arm of the spring being seated on the frame 14. This spring tends to move the segment to that limit of its movement where it is checked by the grip at 13'. In this position it will be seen that the segment 90 projects beyond the frame 14 on one side only.

The handle illustrated happens to be of the plain rectilinear type rectangular in cross section, and tapered from its outer end. 100 The side pieces of the frame 14 are mortised therein and secured by screws or otherwise, whereby the frame is held in proper form to support the gear train and operating segment. The spring 27 tends to move the segment for rotation of the gear 20 in the direction in which the dog will ride the ratchet, and for operating the segment for engagement of the dog and consequent operation of the gear train, an arm 29 is extended from 105 the segment on the side opposite that which is projected from the frame under action 110

of the spring, this arm being suitably offset from the axis of the segment so as to lie in close parallelism with the grip 13 when pressed to the inner limit of its movement, 5 at which time the segment will have completed a movement nearly corresponding to the length of its arc. The arm 29 is T-shaped in cross section, with the major transverse portion disposed outwardly so 10 that a broad surface is presented for engagement by the fingers of an operator, and in the side of the grip 13 there is formed a narrow slot or channel 29' to receive the narrow part of the arm so that the broad 15 part lies nearly or quite flush with the grip, an inconspicuous catch 30 being mounted on the grip by which the arm is secured at the inner limit of its movement, which catch may be of any suitable kind. A hand 20 rest 31 is formed on one side of the grip adapted to rest on the hand close to the base of the fore-finger, as shown in Fig. 5, the pressure of the thumb being sufficient to retain the grip within the palm, and all the 25 digits may thereby be used for operating the arm 29.

The fan blades are curved so as to propel a current of air away from the handle when the gears are rotated under manipulation 30 of the arm 29, and it is found that the momentum of the fan and gears is sufficient to cause their continuous movement with a comparatively slow oscillation of the arm 29 producing a strong current of air. Use 35 of the article has also demonstrated that it is not difficult nor awkward to properly support a sunshade and at the same time manipulate the operating arm 29.

The rest 31 may be omitted if desired and 40 the device supported by grasping the grip with some of the fingers while others are utilized to operate the arm 29 which need not be pressed entirely against the grip for satisfactory operation of the fan. It will be 45 also found practicable to provide a substitute for the rest 31 which will at the same time be an embellishment, by providing a silk cord loop 32 fixed on the outer end of the grip and of a length to allow insertion of 50 the hand therethrough while the handle is grasped, an ornamental tassel being fixed at the outer part of the loop. A casing 33 somewhat pear-shaped and quite small, formed of any suitable material and fixed to 55 the frame 14, completely incloses the mechanism, and adds to the attractiveness of the handle.

The manner in which the side pieces of the frame are utilized to form a threaded shank 60 for screwing into a parasol or umbrella

stem is particularly effective and economical. The sides are bent toward each other immediately above the small gear 17 and extended in parallel relation. These parallel parts are initially made slightly broader than the 65 opening for which they are to be fitted. They may be bent into semicircular form, transversely, at their outer parts so that when put together they form a round shank and when this is threaded it possesses ample 70 strength for the attachment of the handle. The attachment of the shank to the stem of a parasol in this way would be sufficient to hold the frame in form without special fastenings, but as heretofore embodied a small 75 screw or rivet 34 has been used to secure these parts together so that the handle and mechanism may be detached from the parasol and used as a fan alone, when it is very efficient as a hair drier or for other uses 80 where a strong draft is desired. Stays or stiffeners 35 may also be used to prevent the sides of the frame from being pressed in, although these are not believed essential. 85

There is illustrated in Fig. 9 an adaptation of the device to that form of handle having a crook at its outer part, the crook being grooved on its inner side and the lever 29'—which is adapted to be operated in the same manner as the lever 29—has its 90 outer end disposed for oscillation within the groove. The groove stops short of the outer end of the crook, and the oscillation of the lever may be limited thereby. In this way, liability of the lever becoming engaged 95 in delicate fabrics in the garments of the user is obviated. By the formation of the lever with the cross section illustrated, it is inconspicuous while yet possessing ample 100 strength.

What is claimed is:

In a device of the class described, a stationary grip element, a frame formed of strap iron having two parallel sides, the inner ends of these sides being secured against 105 opposite sides of the grip, a fan driving mechanism mounted therebetween, a fan carried thereby, means to operate the mechanism, the upper end of the frame having its opposed sides at the outer end bent into 110 semicircular form in cross-section and disposed in close contact to form a cylindrical shank, the shank being threaded.

In testimony whereof I have hereunto set my hand in presence of two subscribing 115 witnesses.

WASABUROW TAKESUYE.

Witnesses:

JAMES N. KIMBALL,
M. H. VAN DYKE.
